(57) **CLAIM**

The ornamental design of a remote control for drug infusion pump, as shown and described.

DESCRIPTION

FIG. 1 is a right side view of a remote control for drug infusion pump;

FIG. 2 is a left side view of a remote control for drug infusion pump;

FIG. 3 is a front side view of a remote control for drug infusion pump;

FIG. 4 is a rear view of a remote control for drug infusion pump;

FIG. 5 is a top view of a remote control for drug infusion pump;

FIG. 6 is a bottom view of a remote control for drug infusion pump;

FIG. 7 is a first isometric view of a remote control for drug infusion pump;

FIG. 8 is a second isometric view of a remote control for drug infusion pump; and,

FIG. 9 is a third isometric view of a remote control for drug infusion pump.
